Primary Examiner — Shery Lane*Assistant Examiner* — Nicole C Shiflet(74) Attorney, Agent, or Firm — Michael E. Tschupp; Andre Pallapies; Brandon G. Braun(57) CLAIM

The ornamental design for a griddle for a range, as shown and described.

DESCRIPTION

FIG. 1 is a front perspective view of a griddle for a range according to our new ornamental design;

FIG. 2 is a front view thereof; and,

FIG. 3 is a top view thereof.

The broken lines represent environment or structure of the kitchen appliance and do not form any part of the claimed design.

1 Claim, 1 Drawing Sheet(56)
